CONTROL SYSTEM

Filed Feb. 17, 1928

UNITED STATES PATENT OFFICE

HENRY D. JAMES, OF SWISSVALE, PENNSYLVANIA, ASSIGNOR TO WESTINGHOUSE ELECTRIC & MANUFACTURING COMPANY, A CORPORATION OF PENNSYLVANIA

CONTROL SYSTEM

Application filed February 17, 1928. Serial No. 255,048.

The invention relates generally to systems of control and more particularly to the system of control for motors employed in operating hoisting apparatus.

5 The object of the invention, generally stated, is to provide for controlling the lowering speed of electric motors employed in operating hoists or apparatus having similar characteristics.

10 A more specific object of the invention is to provide for lowering the hoist at relatively high speeds when the hoist is unloaded or carrying a light load and to automatically prevent it from exceeding a safe lowering speed when heavily loaded.

15 A further object of the invention is to provide for maintaining an electromagnetic brake energized and released at all times when the motor is being operated to either raise or lower the hoist.

For a better understanding of the invention, reference may be had to the following description taken in conjunction with the accompanying drawing, wherein:

20 The figure is a schematic illustration of a control system arranged in accordance with my invention.

In the drawing, an electric motor 1 of the direct current series type is shown provided 25 with a field winding 2 and an armature 3 which may be suitably coupled to the operating mechanism of a hoist. Since the construction of hoists and the manner of installing motors for operating them is well 30 known, it is not deemed necessary to illustrate the same.

A drum controller 4 having a plurality of contact segments is provided for controlling the operation of the motor 1. The contact segment 5 of the drum controller 4 is disposed to engage the contact finger *a* which in turn is connected to line conductor L1. Contact segment 6 engages contact finger *b* to complete an energizing circuit for the actuating coil 21a of the electromagnetic line contactor 21. Contact segment 7 engages contact finger *c* for completing the energizing circuit for the actuating coils 22a and 23a of the other line contactors 22 and 23,

which circuits, when completed, effect the closing of the contactors 21, 22 and 23.

Therefore, when the drum controller 4 is moved in the indicated direction "raise" to position 1, contactors 21, 22 and 23 are closed and establish a power circuit for the motor 1 which may be traced from line conductor L2 through contactors 22 and 21, the armature 3, series field winding 2, a resistor 32, the electromagnetic brake coil 43a, resistor 34, contactor 23 to line conductor L1. The motor is caused to operate in the proper direction for raising the hoist.

Resistors 32 and 34 are provided for preventing excessive starting currents in the motor and also for making it possible to operate the motor at different speeds. In order to short circuit the sections 28, 29 and 31 of the resistor 34 and the resistor 32, the electromagnetic contactors 24, 25, 26 and 27, respectively, are employed. When the drum controller 4 is moved through the different indicated "raise" positions 2, 3, 4 and 5, contact fingers *d*, *e*, *f* and *g* on the controller engage the contact segments 8, 9, 10 and 11 in the order named, completing the energizing circuits for the actuating coils 24a, 25a, 26a and 27a, respectively, closing the accelerating contactors 24, 25, 26 and 27, which contactors in closing, short circuit the respective sections 28, 29 and 31 of the current limiting resistor 34 and also the resistor 32.

It will be readily seen that if it is desired to operate the motor at a predetermined speed, the drum controller may be disposed in one of the different positions 1, 2, 3, 4 and 5, thereby allowing different portions of the resistors to remain in the motor circuit.

When it is desired to lower the hoist, the motor is reversed by moving the drum controller 4 in the direction indicated "lower" and when in the first position, the contact segments 12, 13, 14, 15, 16, 17 and 18 of the drum switch engage the contact fingers *a*, *c*, *d*, *e*, *f*, *g* and *h*, respectively, completing the energizing circuits for the actuating coils 22a, 23a, 24a, 25a, 26a, 27a, 36a and 37a, closing the contactors 22, 23, 24, 25, 26, 27, 36 and 37 respectively. The closing of con-

tactors 22, 36 and 23 completes a circuit for energizing the field winding 2 of the motor, which circuit may be traced from line conductor L2 through contactors 22 and 5 36 and resistor 38 which is provided for protecting the motor when connected to operate in the lowering direction, series field winding 2, contactor 27 which in the first position is closed, the brake coil 43a, contactors 26, 25, 24 and 23 to line conductor L1. Upon the closing of contactor 37, a power circuit for the armature of the motor 10 is also established and the direction of flow of current through the armature is reversed 15 and may be traced as flowing from line conductor L2 through contactors 22 and 36, resistor 38, armature 3, relay coil 39, dynamic braking resistor 42, contactors 37 and 23 to line conductor L1. When the motor 20 is connected in this manner, it is connected to operate as a shunt wound motor. Since the resistors 32 and 34 are short-circuited, the greatest amount of field strength is provided 25 for starting the motor in the lowering direction. In order to increase the lowering speed of the motor, the resistors 32 and 34 may be inserted in series circuit relation with the series field winding 2 by actuating the drum switch through the positions 2, 3, 30 4 and 5 as indicated, deenergizing the actuating coils 24a, 25a, 26a and 27a of the contactors 24, 25, 26 and 27, respectively, and allowing them to fall open, as the contact segments 14, 15, 16, and 17 pass out of engagement with the contact fingers d, e, f and 35 g. The resistors 32 and 34 so inserted reduce the magnetic field of the motor permitting it to run at higher speeds. When the drum controller 4 is moved to position 5 40 "lower", contact segment 19 comes into engagement with contact member i, completing an energizing circuit for the actuating coils 44a, 45a, 46a, 47a of contactors 44, 45, 46, and 47, respectively, which contactors are 45 provided for controlling the amount of the resistor 49 connected in shunt circuit relation to the series field winding 2 and resistor 32. The resistor 49 is provided for further controlling the lowering speed of the motor, 50 and is connected in shunt relation to the series field winding 2 for also reducing the field strength of the motor. The purpose of connecting the resistor 49 across the resistor 32, as well as the field winding 2 is 55 because the resistance value of the field winding is so low that if the resistor 49 were connected in shunt relation to the field winding alone, the varying contact resistance of the contactors 45, 46 and 47 would greatly 60 affect the operation of the system.

The energizing circuit for the actuating coils of the contactors 44, 45, 46 and 47 extends from line conductor L1 through contact segments 12 to 19 inclusive, contact 65 finger i, back contact members or interlocks

51b, 52b, 53b, and 54b of the respective current limit relays 51, 52, 53 and 54 and the actuating coils 44a, 45a, 46a and 47a, respectively, which coils are connected in parallel circuit relation, to conductors L1 and L2. 70 The closing of contactor 44 completes a circuit extending from one side of the series field winding 2 through contactor 44, resistor 49, resistor 32 to the other side of the series field winding. When contactor 44 is 75 initially closed, contactors 45, 46 and 47 are also closed, and, sections 56, 57 and 58 of the resistor 49 are short-circuited.

In order to control the operation of the contactors 44, 45, 46 and 47 automatically, 80 so that the speed of the motor will be prevented automatically from exceeding a safe lowering speed when the hoist is heavily loaded, the current relays 51, 52, 53 and 54 are provided, upon which are mounted interlocks 51b, 52b, 53b and 54b which complete the circuits for the actuating coils 44a, 45a, 46a and 47a when the current relays are deenergized, which occurs whenever the machine 1 is operating as a motor. The polarized relay 41 is provided in order to render the relays 51, 52, 53 and 54 responsive to the counter-electromotive force of the motor, when the motor is "overhauled" by heavy lowering load and caused to operate 90 as a generator. A coil 55 of the relay 41 is connected in shunt relation with the armature 3 of the motor and a coil 39 is connected in series circuit relation with the armature 3. The coils are disposed to so 100 affect each other differentially that the relay shall remain closed when the motor is operating as a motor, but upon the reversal of the direction of flow of current through the series coil 39 when the motor is being 105 driven as a generator, the relay is actuated to its circuit interrupting position and, inasmuch as it is connected in circuit relation with the actuating coil 22a of the contactor 22, line contactor 22 falls open, disconnecting 110 the motor from the power supply.

When contactor 22 opens, interlock 22b completes a circuit extending from one side of the armature 3 through the series coil 39 of the relay 41, interlock 22b, the actuating coil 51a of relay 51 to the other side of the armature 3. The relay 51 may be constructed to respond to predetermined current conditions. Consequently, when the motor is driven as a generator by the lowering load and reaches a predetermined speed, or generates a predetermined voltage the relay 51 is actuated. When actuated, the interlock 51b interrupts the circuit for the actuating coil 45a of contactor 45, permitting the contactor 45 to fall open, inserting section 56 of resistor 49 in shunt relation with the series field winding 2, which causes more current to flow through the series field winding, increasing the magnetic field of 130

the motor, which tends to decrease the speed of the motor, or, in other words, dynamically brake the same.

When relay 51 is closed, contact member 51c completed the energizing circuit for actuating coil 52a of relay 52 which is connected in parallel circuit relation with the actuating coil 51a. The relay 52 may be constructed with similar characteristics to that of relay 51 so that it will respond to a predetermined generated voltage 1, which if exceeded, will effect its closure, resulting in the opening of contactor 46 in the same manner as contactor 45 and if the load still continues to drive the motor as a generator with increasing speed, the relays 53 and 54 will close in sequence, until the entire resistor 49 is in shunt relation with the series field winding, thus progressively increasing the field strength of the series field winding 2, causing the motor to be operated as a generator at full field, which automatically prevents the hoist from running away with the motor when loaded within the capacity of the hoist.

When the motor is running in either direction, if the drum controller 4 is moved to the "off" position, interlock 23b on contactor 23 establishes a dynamic braking circuit for the motor which extends from one side of the armature 3 through the coil 39 of the relay 41, dynamic braking resistor 42, interlock 23b, series field winding 2 to the other side of the armature. The ohmic resistance of the dynamic braking resistor 42 may be of a very low value, in order that the motor shall develop a high dynamic-braking effort. It will be observed that in this system the electromagnetic brake coil 43a is connected in such a manner that it will be energized whenever the drum controller is disposed in an operating position, accordingly, maintaining the brake 43 inoperative whenever the hoist is being raised or lowered. It will also be noted that when the motor is connected to operate as a shunt wound motor to lower the hoist, and is caused to operate as a generator, circuits will be established automatically to effect operation of the motor as a series wound generator.

Since the relay 41, when open, operates to disconnect the motor from the source of supply and to connect the motor for operation as a series-wound generator, heavy loads may be lowered with safety and at permissible speeds.

While the illustrated example constitutes a preferred embodiment of the invention, it is not desired to limit the invention strictly to the details shown, since the embodiment described may be considerably varied without departing from the spirit of the invention as defined in the appended claims.

I claim as my invention:

65 1. In a control system, in combination, a

dynamo electric machine provided with an armature and a field winding, means for connecting the armature and field winding in series circuit relation for operation in one direction and for connecting the armature winding and field winding in parallel circuit relation for operating the motor in the other direction, a variable resistor connected in shunt relation to the field winding, and means responsive to the speed of the motor when running in one direction for establishing a dynamic braking circuit and varying the variable resistor.

2. In a motor control system, in combination, a direct current motor having a field winding and an armature winding, a source of current, means for connecting the armature winding and field winding in series circuit relation to the source of current for operating the motor in one direction and for connecting them in parallel circuit relation for operation in the reverse direction, a variable field resistor, means for connecting said variable resistor in shunt circuit relation to the field winding when the field winding is connected in parallel circuit relation to the armature winding, and electro-responsive means for varying said resistor in accordance with the voltage developed by said motor acting as a generator.

3. In a control system for hoist operating motors, in combination, a direct current motor, a source of energy, means for connecting the motor to the source of energy to operate as a series wound motor for raising a load and for connecting it to operate as a shunt wound motor for lowering a load, means for varying the field strength of the motor when operating as a shunt wound motor to control the speed of the motor when lowering a load, and means for automatically disconnecting the motor from the source of energy when the motor is lowering a load and the load causes the motor to operate as a generator and means responsive to said disconnecting means for automatically rendering the field varying means responsive to the speed of the motor.

4. In a control system for hoist operating motors, in combination, a direct current motor, a field winding and an armature winding for the motor, a current limiting resistor for the motor, a source of current, a manually operable controller, switching mechanism responsive to the manually operable controller when operating in one direction for connecting the armature winding and the field winding and the resistor in series circuit relation to the source of current and for short circuiting the resistor, other switching mechanism responsive to the controller when actuated in the reverse direction for reversing connection of the armature winding and connecting the field winding in parallel circuit relation to the arma-

- ture winding, means for varying the strength of the motor field when connected to operate as a shunt motor and means for automatically disconnecting the motor from the source of current when a heavy lowering load causes the motor to operate as a generator, said means rendering the field varying means responsive to the voltage generated by the motor to regulate the speed of the motor.
5. In a control system for hoist operation, in combination, a reversible direct current motor, a field winding, an armature winding, and a current limiting resistor for the motor, a source of current, a manually operable switch for connecting the armature winding, the field winding and the current limiting resistor in series circuit relation to the source of current when the manually operable switch is moved to connect the motor for operation in a hoist raising direction, means responsive to the manually operable switch for short circuiting the current limiting resistor, means also responsive to said switch when operated in the reverse direction for reversing the directions of current to the armature and for connecting the field winding and the current limiting resistor in series circuit relation to the source 30 of current and in parallel circuit relation to the armature winding for lowering a load, means automatically responsive to the change in direction of current in the armature winding for disconnecting the motor from the source of current when a lowering load causes the motor to operate as a generator and for establishing a circuit for dynamically braking the motor when so operated, a variable resistor for changing the field strength of the motor when operating as a generator and means automatically responsive to the voltage generated by the motor for controlling the field resistor to regulate the lowering speed of the load.
45. 6. In a control system for hoist operating motors, in combination, a reversible motor, a field winding, an armature winding and a current limiting resistor for the motor, a source of current, means for connecting the armature winding, the field winding and the current limiting resistor in series circuit relation to the source of current to operate the motor to raise a load and means for short circuiting the current limiting resistor, means for connecting the armature winding to the source of current and means for connecting the field winding in series circuit relation with the current limiting resistor to the source of current when operating the motor to lower a load, a variable resistor for varying the current in the field winding and means for automatically varying the resistor, means for disconnecting the motor from the source of current when it is caused to operate as a generator by a lower-

ing load, said means rendering the resistor varying means operable to limit the lowering speed of the load, an electromagnetic brake for braking the motor and a circuit for maintaining the brake inoperative at all times that the motor is connected for operation as a generator.

7. In a control system, in combination, a direct current motor for operating hoisting apparatus, a field winding and an armature winding for the motor, a source of current, means for connecting the motor to said source to operate as a series wound motor when raising the hoist and to connect it to operate as a shunt wound motor when lowering the hoist, means for varying the field strength of the field winding when connected for lowering a load, and means responsive to the voltage generated by the motor when it is caused to operate as a generator by a lowering load for rendering the field varying means responsive to voltage generated to automatically prevent the motor exceeding a safe lowering speed.

8. In a control system for electrically operated hoisting apparatus, in combination, a direct current motor, means for connecting the motor to operate as a series wound motor for raising a load and for connecting it to operate as a shunt wound motor for lowering a load, current and voltage responsive means disposed to disconnect the motor from the source when a lowering load causes the motor to operate as a generator, means for establishing a circuit for effecting dynamic braking when the motor circuit is interrupted, voltage responsive means for varying the shunt field of the motor when operating as a generator, an electromagnetic brake for braking the motor, and a circuit for energizing the brake to render it inoperative when the motor is energized.

In testimony whereof, I have hereunto subscribed my name this 10th day of February, 1928.

HENRY D. JAMES.
